F. M. NICKERSON,
PLAYING ATTACHMENT FOR ZITHERS,
APPLICATION FILED MAR. 12, 1919.

1,352,618.

Patented Sept. 14, 1920

UNITED STATES PATENT OFFICE.

FREDERICK M. NICKERSON, OF EVERETT, MASSACHUSETTS, ASSIGNOR TO THE PHONO-HARP COMPANY, OF EAST BOSTON, MASSACHUSETTS, A CORPORATION OF MAINE.

PLAYING ATTACHMENT FOR ZITHERS.

1,352,618.

Specification of Letters Patent. Patented Sept. 14, 1920.

Application filed March 12, 1919. Serial No. 282,154.

To all whom it may concern:

Be it known that I, FREDERICK M. NICKERSON, a citizen of the Dominion of Canada, residing at Everett, in the county of Middlesex and State of Massachusetts, have invented new and useful Improvements in Playing Attachments for Zithers, of which the following is a specification.

The object of this invention is to provide a simple improved attachment by which the chord strings of a zither or like instrument may be played. Such attachments are sometimes termed "left-hand" attachments, as the groups of chord strings are usually located on the left side of the melody strings which are arranged to furnish either a diatonic or chromatic scale. Each of the groups of chord strings usually consists of four strings, one tuned to constitute the fundamental bass, and the others tuned to furnish a triad in harmony therewith. An attachment embodying the present invention preferably is provided with one hammer for striking the bass string and a hammer for 25 striking the associated strings of the same group of chord strings, so that there are two hammers for each group.

On the accompanying drawing,—

Figure 1 represents in plain view a portion 30 of a zither provided with a "left-hand" attachment embodying the invention.

Fig. 2 represents a plan view of a portion of the attachment on a larger scale.

Fig. 3 represents a section on the line 3—3 35 of Fig. 2, and shows the hammer in a normal inactive position.

Fig. 4 is a similar view, but shows the hammer in dotted lines as engaged with the string, and in full lines as raised and ready 40 to be released.

Fig. 5 represents a section on the line 5—5 of Fig. 1.

Fig. 6 illustrates a portion of the frame and shows how the hammers are mounted.

Fig. 7 illustrates a portion of the hand-rest and cover.

Fig. 8 represents a perspective view of one of the hammers.

Referring to the drawings,—I have shown 50 a portion of a zither comprising a sounding board 10, and having a series of melody strings, some of which are indicated at 11, and four groups of chord strings, each group comprising a bass string 12, and three strings 55 13 furnishing a triad.

The attachment comprises a hammer 14 for each bass string and a hammer 15 for the remaining strings of each group. These hammers may be all identical in construction, although, if desired, the hammers of 60 the triad strings may be somewhat wider than those for the bass strings. These hammers are all pivoted or fulcrumed near their rear ends upon a pivot, which may consist of a rod or wire 16. Each hammer may, if 65 desired, be made of wood or other suitable material, and has a shank with a flat upper face 17, and at its free end is formed or provided with a finger-piece consisting of an upwardly extending projection 18, the 70 front face of which is preferably concave. Each hammer has a notch 19 to receive the pivot. This construction permits the independent detachment of each hammer. The hammers are engaged by leaf springs 20, so 75 arranged that the pressure of the springs upon the flat top faces of the hammers normally holds the hammers at an angle to the strings, as shown in Fig. 3. When the operator engages the finger-piece 18 and lifts 80 the hammer to the position shown by the full lines in Fig. 4, the free extremity of the spring is raised, thus storing power in the spring; and then, when the finger-piece is released, the spring forces the hammer 85 downwardly until the head of the hammer engages the string as shown by the dotted lines in the last-mentioned figure. When in the last-mentioned position, the rear extremity of the hammer (in the rear of the 90 pivot 16) lifts or flexes the spring, so that, as soon as the hammer head has struck the string, the spring returns the hammer to its normal position. The head of the hammer may be formed in any desirable way as by 95 securing to the shank a piece of felt or other material 201.

It is quite evident that any suitable frame or holder for the action may be employed and that it may be located at any convenient 100 point on the zither. As shown, the rear ends of the springs are secured in the bar 21. This bar is secured on a frame comprising parallel end bars or blocks 22, which are fastened by screws 23 to the sounding 105 board of the zither, so that the hammers and springs will extend longitudinally of the associated strings.

The springs may be all formed integrally, if desired, so as to project from a strip 24 110

(see Fig. 6), but of course they may be separate leaf springs. There is an advantage, however, in stamping or cutting them from a sheet of resilient spring metal, as the correct spacing of the individual spring members 20 is secured. The securing bar consists of a sheet of metal folded to provide two members 25, 26, which embrace the strip 24 and rigidly clamp it. At its end the bar has forwardly projecting fingers 27 through which pass the screws 28 which fasten said bar to the end blocks 22 of the frame. The upper faces of said blocks are recessed as at 29 and the screws 28 pass down into the blocks between the end walls of said recesses. Hence, by adjusting the screws, the bar 21 may be tilted slightly to adjust the ends of the springs simultaneously toward or from the strings.

20 The action is provided with a combined hand-rest and cover which consists of a thin metal plate. It has a top wall 291, end walls 30 which embrace the blocks 22, a rear wall 31 which laps the rear ends of the blocks, and a front wall 32 lapping the front ends of said blocks. The cover has a vertical wall 33 and a horizontal wall 34, the latter being in a plane below that of the hand-rest portion or top wall 291 of the cover. The front wall has slots 35, and the wall 34 has slots 36 to receive the free ends of the hammers so that the finger-pieces lie in the reentrant angle formed by said walls. In forming the slots 36, tongues or lips 37 are bent downwardly into parallelism to furnish spacers for the hammers to prevent them from being laterally dislocated. The cover covers or conceals all of the action with the exception of the finger-pieces 18, and it is secured in place by the same screws 23 which fasten the blocks 22 to the sounding board. It will be observed from Fig. 4 that the upper end walls 38 of the slots serve as stops to limit the upward movement of the hammers when they are lifted preparatory to causing them to strike the strings. The rear wall 31 has tongues or lips 39 which rest upon the rear ends of the blocks, and which are in the same horizontal plane as the wall 34 which rests upon the front ends of said blocks.

55 It is quite clear that various changes may be made in the details of construction herein described without departing from the spirit and scope of the invention as defined in the claims.

Having thus explained the nature of my said invention and described a way of making and using the same, although without attempting to set forth all of the forms in which it may be made or all of the modes of its use, what I claim is:—

60 1. The combination with a zither, of a playing attachment therefor, comprising a hammer arranged above the strings, a pivot 65 on which said hammer is fulcrumed near its

rear end, a leaf spring normally bearing upon the hammer on both sides of the pivot and holding the hammer head apart from its associated string or strings, substantially as set forth.

2. The combination with a zither, of a left-hand playing attachment for the groups of chord strings, comprising a frame, a pivot rod supported by said frame transversely of the strings, a plurality of inflexible hammers, each fulcrumed near its end on said pivot, a plurality of leaf springs associated with said hammers, each spring normally engaging its associated hammer in front and in rear of said pivot and holding the hammer head apart from said string, and means for securing the rear ends of said springs to said frame.

3. The combination with a zither, of a left-hand playing attachment for the groups of chord strings, comprising a frame, a pivot rod supported by said frame transversely of the strings, a plurality of inflexible hammers, each fulcrumed near its end on said pivot, a plurality of leaf springs associated with said hammers, each spring normally engaging its associated hammer in front and in rear of said pivot and holding the hammer head apart from said string, means for securing the rear ends of said springs to said frame, and a hand rest located above the springs and serving as a stop to limit the upward movement of the hammers.

4. The combination with a zither, of a left-hand playing attachment for the groups of chord strings, comprising a frame, a pivot rod supported by said frame transversely of the strings, a plurality of inflexible hammers, each fulcrumed near its end on said pivot, and having at its headed end an upwardly extending finger-piece by which the said headed end may be lifted by the operator, a plurality of leaf springs associated with said hammers, each spring normally engaging its associated hammer in front and in rear of said pivot and holding the hammer head apart from said string, and means for securing the rear end of said springs to said frame.

5. The combination with a zither, of a left-hand playing attachment for the groups of chord strings, comprising a frame, a pivot rod supported by said frame transversely of the strings, a plurality of inflexible hammers, each fulcrumed near its end on said pivot, a strip of spring metal having integral therewith a plurality of leaf springs engaging said hammers, and a cross bar by which said strip is secured to said frame.

6. The combination with a zither, of a left-hand playing attachment for the groups of chord strings, comprising a frame, a pivot rod supported by said frame trans-

versely of the strings, a plurality of inflexible hammers, each fulcrumed near its end on said pivot, a plurality of leaf springs engaging said hammers, a securing bar for 5 said springs consisting of a folded strip between the members of which the springs are clamped, and means for securing said bar to said frame.

7. The combination with a zither, of a 10 left-hand playing attachment for the groups of chord strings, comprising a frame, a pivot rod supported by said frame transversely of the strings, a plurality of inflexible hammers, each fulcrumed near its end 15 on said pivot, and having at its headed end an upwardly extending finger-piece by which the said headed end may be lifted by the operator, a plurality of leaf springs associated with said hammers, each spring 20 normally engaging its associated hammer in front and in rear of said pivot and holding the hammer head apart from said

string, means for securing the rear ends of said springs to said frame, and a cover affording a hand-rest, and having at its 25 front portion horizontal and vertical walls forming a reentrant angle, said walls being slotted to receive and expose the finger-pieces on the hammers.

8. A zither playing attachment comprising 30 a supporting frame, a pivot rod supported by said frame transversely of the strings, a hammer having a notch near its end riding on said wire, whereby the hammer is fulcrumed on said wire, and a leaf 35 spring contacting with the hammer on both sides of the fulcrum, whereby the hammer is held against displacement from said rod and in normal position out of contact with the strings. 40

In testimony whereof I have affixed my signature.

FREDERICK M. NICKERSON.
